George G. Hasbrouck

UNITED STATES PATENT OFFICE.

GEORGE G. HASBROUCK, OF NEW YORK, N. Y., ASSIGNOR TO THE GRAND UNION SALES COMPANY, INC., OF NEW YORK, N. Y., A CORPORATION OF NEW YORK.

DESIGN FOR A SEWING-MACHINE COVER-CASE.

59,841.

Specification for Design.

Patented Nov. 29, 1921.

Application filed April 7, 1920. Serial No. 372,089. Term of patent 14 years.

To all whom it may concern:

Be it known that GEORGE G. HASBROUCK, a citizen of the United States, residing at New York, in the county of New York and State of New York, has invented a new, original, and ornamental Design for a Sewing-Machine Cover-Case, of which the following is a specification, reference being had to the accompanying drawing, forming part thereof.

The figure is a perspective view of a sewing machine cover case, showing my new design.

What I claim:

The ornamental design for a sewing machine cover case, as shown.

GEORGE G. HASBROUCK.
